UNITED STATES PATENT OFFICE.

MAX PEINLICH, OF WHITE PLAINS, NEW YORK, ASSIGNOR TO ALJAC LIGHTING FIXTURE CO., INC., OF NEW YORK, N. Y., A CORPORATION OF NEW YORK.

DESIGN FOR A PEDESTAL BASE.

Application filed November 17, 1928. Serial No. 28,923. Term of patent 3½ years.

To all whom it may concern:

Be it known that I, MAX PEINLICH, a citizen of the United States, residing at White Plains, in the county of Westchester and State of New York, have invented a new, original, and ornamental Design for Pedestal Bases, of which the following is a specification, reference being had to the accompanying drawing, forming part thereof.

In the drawing—

Figure 1 is a side elevation of a pedestal base, showing my new design; and

Figure 2 is a top plan view showing a portion of the ornamentation, the blank space between the marginal lines being designed to contain a repeat of the ornamentation shown.

I claim:

The ornamental design for a pedestal base, as shown and described.

MAX PEINLICH.
